CLAIM

The ornamental design for a laundry appliance, as shown and described.

DESCRIPTION

FIG. 1 is a front perspective view of a first embodiment of a laundry appliance showing our new design;

FIG. 2 is a top view thereof;

FIG. 3 is a front view thereof;

FIG. 4 is a right side view thereof;

FIG. 5 is a left side view thereof;

FIG. 6 is a front perspective view of a second embodiment of a laundry appliance showing our new design;

FIG. 7 is a top view thereof;

FIG. 8 is a front view thereof;

FIG. 9 is a right side view thereof; and,

FIG. 10 is a left side view thereof.

The unshown bottom surface and rear surface of the laundry appliance forms no portion of the claimed design.
